(57) **CLAIM**

The ornamental design for a cutting board as shown and described.

DESCRIPTION

FIG. 1 is a top plan view of a cutting board, showing my new design;

FIG. 2 is a bottom plan view thereof;

FIG. 3 is a front elevation view thereof;

FIG. 4 is a rear elevation view thereof;

FIG. 5 is a left-side elevation view thereof; and,

FIG. 6 is a right-side elevation view thereof.

The cutting board has been shown with symbolic breaks. The appearance of any portion of the article between the break lines forms no part of the claimed design. The broken lines words show unclaimed portions of the cutting board and forms no part of the claimed design.
